UNITED STATES PATENT OFFICE.

CARL KEIBEL, OF FOLSONG, NEAR TAUER, GERMANY.

CANDLE-HOLDER.

SPECIFICATION forming part of Letters Patent No. 273,103, dated February 27, 1883.

Application filed August 3, 1882. (No model.) Patented in Germany July 17, 1882; in Belgium July 17, 1882, No. 58,492; in England July 17, 1882, No. 3,390, and in France July 18, 1882, No. 150,152.

To all whom it may concern:

Be it known that I, CARL KEIBEL, a subject of the King of Prussia, residing at Folsong, near Tauer, German Empire, have invented certain new and useful Improvements 5 in Candle-Holders; and I do hereby declare the following to be a full, clear, and exact description of the invention, such as will enable others skilled in the art to which it appertains 10 to make and use the same, reference being had to the accompanying drawings, and to letters or figures of reference marked thereon, which form a part of this specification.

My invention relates to improvements in 15 candle-holders or attachments to candlesticks or chandeliers, and has for its object to provide means whereby candles of different diameters may be held by the holder without reducing or enlarging the diameter of such candles by shaving the end or wrapping paper or 20 other material upon said end to reduce or enlarge its diameter to make it fit the holder or candlestick.

The invention consists, essentially, of a 25 preferably conical or tapering sleeve or thimble, screw-threaded upon its interior periphery, and preferably cut away to form tongues or fingers, for purposes hereinafter described; and the invention further consists in the combination, 30 with the screw-threaded sleeve, of an inclosing sleeve or thimble, provided in its bottom with openings, for purposes hereinafter set forth; and the invention further consists in constructing the holder in such manner as to 35 adapt it for general use on candlesticks or holders of usual construction.

In the accompanying drawings, Figure 1 is an 40 elevation of an ordinary candlestick provided with the improved holder, shown in section. Fig. 2 shows the holder and part of the candlestick in elevation. Fig. 3 is a plan view of the holder and its inclosing-sleeve. Fig. 4 is a plan view of the inclosing-sleeve detached. Figs. 5 and 6 show the holder detached in 45 section and by a plan view, respectively, the sections being taken on line $x-x$ of the latter figure. Fig. 7 shows in section the holder with its inclosing-sleeve mounted upon a plug for application to candlesticks of usual construction.

Like letters of reference indicate like parts in the above figures of drawings.

The holder may be permanently attached to or formed on a candlestick, and made of any suitable material in which a screw-thread 55 may be molded, cut, or spun—such as metal, sheet metal, glass, or porcelain, or other suitable material—and when so constructed the holder may or may not be provided with a screw-threaded shank to screw it into a boss or bearing formed in the upper tubular part of the candlestick. I prefer, however, to make the holder, with its inclosing-sleeve, detachable 60 from the candlestick, so as to facilitate the cleaning thereof, or so as to readily replace it 65 in case it should become broken when formed of some fragile material.

The holder is adapted for use with or without an inclosing-sleeve. In practice I preferably employ such a sleeve to receive and hold 70 the drippings of the candle, as well as the cuttings taken from the end thereof when the candle is screwed into the holder. If preferred, however, the candlestick may be provided with a projecting, flaring, or other flange 75 or rim on a level with the upper face of the boss, in which the holder is seated, not to receive the drippings from the candle only, but also to receive the cuttings taken from the end 80 of the candle when it is screwed into the holder.

The holder itself, when made of a rigid material, is made to taper from its flaring mouth downward, to adapt it to hold candles of different diameters. This is, however, not absolutely necessary when the holder is made of some more or less flexible material, in which case the holder may be made practically tubular, since the fingers or tongues will be more 90 or less elastic, and said tongues forming a trumpet-shaped or flaring mouth, candles of various diameters may be held thereby, as the tongue will yield radially to a greater or less extent either way. When, however, the holder 95 is constructed of a more or less flexible material, the tongues should possess sufficient rigidity to insure their cutting into the end of and hold the candle securely.

To facilitate the removal of the drippings 100

and cuttings, and to avoid the soiling of the candlestick, the inclosing-sleeve is preferably made detachable from the holder proper, and is provided in its bottom with a central aperture and two or more circumferential openings, that afford access through its under side, and whereby such drippings or cuttings may be readily removed.

In the accompanying drawings, C indicates 10 the candlestick, provided with a boss or seat, c, that has a central screw-threaded opening, c', for the reception of the screw-threaded shank or stem h of the holder H.

The holder H consists of a base-disk, h', to 15 which is securely attached, or upon which is formed, a shank, h, and of three (more or less) fingers or tongues, h², having their upper portions made to flare or curve more or less outwardly, and preferably made to taper from 20 their upper flaring edges to the disk h'. A continuous screw-thread common to all the tongues is formed upon or cut in their inner faces, as shown, each tongue presenting, therefore, upon its vertical faces a series of sharp 25 cutting-points, p, formed by the apex of the salient angle of the screw-threads. This arrangement facilitates the fixing into position of the candle, as the sharp edges will readily bite in and take hold of the candle when screwed 30 into the holder. When the holder is made of sheet metal, the sleeve, after having the screw-thread cut or spun thereon, may then be cut away to form the elastic tongues h², and where 35 the metal is cut away a series of very sharp cutting-points will be formed upon the edges, as above set forth.

The inclosing sleeve or thimble S is tubular, and has a flaring mouth, s, and preferably a recurved flange, s', as shown. In its bottom 40 is formed a central opening, s², through which the shank h of the holder proper passes. It is further provided with two (more or less) circumferential openings, s³, arranged around the central opening, s².

45 The shank h of the candlestick may be provided with any suitable screw-thread, either a screw-thread adapted to be screwed to a metallic seat, or a wood-screw thread, as shown in Fig. 7, to adapt it to be mounted upon a 50 plug or cork, B, for use with and as an attachment for any usual form of candlestick.

It will be seen that when the shank of the holder H is passed through the opening s², and the holder screwed into its seat or plug, 55 the latter will firmly hold the sleeve or thimble S in position.

Having now described my invention, what I claim is—

1. The combination, with a candlestick or 60 analogous device, of a holder composed of an interiorly-screw-threaded sleeve tapering from top downward, into which candles of various diameters may be screwed, as described.

2. The combination, with a candlestick or analogous device, of a holder composed of a 65 series of fingers or tongues provided upon their inner faces with a continuous screw-thread common to all the tongues, between which the candle is screwed, and by which it is securely held, as described.

3. The combination, with a candlestick or analogous device provided with a boss or seat having a screw-threaded opening, of a holder composed of a series of tongues or fingers provided upon their inner faces with a continuous screw-thread common to all the tongues, and with a screw-threaded stem or shank, whereby said holder may be detachably connected with said candlestick, as and for the 75 purposes specified.

4. The combination, with a candlestick or analogous device having a boss or seat provided with a screw-threaded opening, of a candle-holder provided with a screw-threaded shank, and an inclosing-sleeve for the same 80 provided in its bottom with openings s³, and adapted to be mounted upon said shank, and held firmly between the holder and seat on the candlestick when said holder is screwed thereto, as described, and for the purposes 85 specified.

5. The combination, with a candlestick or analogous device having a boss or seat provided with a screw-threaded opening, of a holder composed of a tapering sleeve provided 90 with an interior screw-thread and a screw-threaded shank, said sleeve being cut away to form a series of more or less elastic fingers or tongues, having upon their vertical edges a series of cutting-points formed by the apices 95 of the salient angles of said screw-thread, substantially as and for the purposes specified.

6. As a new article of manufacture, an attachment for candlesticks composed of a downwardly-tapering holder formed of fingers or 100 tongues provided upon their inner surfaces with a continuous screw-thread common to all the tongues, said holder being provided with a shank whereby it may be secured to a cork or other plug inserted in any usual candlestick, and whereby candles of different diameters may be held thereby, as set forth.

7. As a new article of manufacture, the herein-described candle-holder H and its inclosing-sleeve S, constructed for operation and attachment to a candlestick of usual construction, 110 substantially as shown and described, for the purpose specified.

In testimony whereof I affix my signature in presence of two witnesses.

CARL KEIBEL.
